UNITED STATES PATENT OFFICE.

FREDERICK P. WOOD, OF DETROIT, MICHIGAN, ASSIGNOR TO AMERICAN CAN COMPANY, OF NEW YORK, N. Y., A CORPORATION OF NEW JERSEY.

DISPENSING-PACKAGE.

1,158,093.

Specification of Letters Patent. Patented Oct. 26, 1915.

Application filed December 1, 1913. Serial No. 803,905.

To all whom it may concern:

Be it known that I, FREDERICK P. Wood, a subject of the Kingdom of Great Britain, residing in Detroit, in the county of Wayne 5 and State of Michigan, have invented a new and useful Improvement in Dispensing-Packages, of which the following is a specification.

This invention relates to improvements in 10 dispensing packages.

Objects of the invention are to provide a pouring spout can or package adapted for containing salt and other similar comminuted substances which is of cheap and simple construction, which is easily manipulated by the user and in which the pouring spout is so arranged that it is held within the can during shipment, thereby permitting stacking of the cans the one on top of the 20 other without danger of injury.

Other objects of the invention are to provide a pouring spout can in which the spout is formed of light sheet metal and is slideable inwardly and outwardly in a slit in one 25 wall of the can and in which a part of the can wall is operated automatically when the spout is moved outwardly, to leave an opening for the material to pass out of the can.

The invention furthermore consists in the 30 improvements in the parts and devices and in the novel combinations of the parts and devices herein shown, described or claimed.

In the drawing forming a part of this specification, Figure 1 is an end view of a 35 can or package showing my improvements in connection therewith. Fig. 2 is a sectional view taken substantially on the line 2—2 of Fig. 1. Fig. 3 is a sectional view similar to Fig. 2 but showing the spout in 40 its extended position and with the flap formed in the end wall, open, and Fig. 4 is a sectional view taken on the line 4—4 of Fig. 3; Figs. 2, 3 and 4 being on an enlarged scale to more clearly illustrate the 45 construction.

In said drawing, the body of the can or package is designated by the reference 10 and as shown, is provided with an end 11, the can being formed of paper or other suitable material, preferably of a fibrous nature. The end 11 has slideably mounted therein a sheet metal pouring spout 12 which is trough-shape in cross section, as shown most clearly in Figs. 1 and 4. The end edges of 55 the pouring spout are turned outwardly in

the form of flanges 23—23 which serve to limit the inward and outward movements of the spout relatively to the end 11. The end 11 of the can is provided with a slit which corresponds in outline and size to the cross 60 sectional contour of the pouring spout 12, and when cut in this manner, the end 11 will have a flap or closure 13 within the spout 12. When the package is being shipped, the pouring spout and flap 13 will be in the position shown in Figs. 1 and 2, but when the consumer wishes to pour out the contents of the can he will insert his finger nail or other suitable device beneath one of the flanges 23 and pull the spout out to the position shown 65 in Fig. 3. The spout 12, near its inner end is provided with projections or teats 14, which, when the spout is pulled outwardly, engage the edges of the flap 13 and swing it outwardly to the position shown in Fig. 3, 70 whereby the contents of the can may be readily poured out. After the user has obtained the desired amount of the can's contents, the spout is forced inwardly and ordinarily the friction between the flap 13 and 75 the pouring spout will be sufficient to return the flap to normal or closed position. But in any event, the user's finger or thumb used in pushing the spout inwardly, will naturally engage the flap 13 and return it to 80 closed position. As shown in dotted lines in Fig. 1, a sticker 15 may be pasted over the end of the pouring spout while the can is 85 being shipped.

From the preceding description, it will be 90 seen that I have provided a simple and efficient pouring spout which will be held in position by the friction between it and the adjacent edges of the wall in which it is slideably mounted, and the arrangement is 95 such that the flap is automatically opened and closed in accordance with the movements of the pouring spout. It will furthermore be noted that when the spout is in its innermost position, the opening is well 100 sealed and by having the spout slideably arranged, I secure another advantage since there is no tendency for the spout to be moved inwardly during the pouring operation should the user rest the spout on the 105 edge of the vessel into which the contents of the can are being poured. Hitherto, where pivoted pouring spouts have been used, the latter have a tendency to close inwardly if they are rested on any support 110

during the pouring operation, with the result that the user has to either hold the pivoted pouring spout free from contact with any other object or must open the pivoted 5 spout several times to obtain the amount desired.

Although I have herein shown and described what I now consider the preferred embodiment of my improvement, yet it will 10 be understood that various changes and modifications may be made without departing from the spirit of the invention, and all such changes and modifications are contemplated as come within the scope of the 15 claims appended hereto.

I claim:—

1. A dispensing package of the character described comprising a can having a trough-shaped sheet metal pouring spout 20 slidably mounted directly in one wall thereof and having a portion of the wall arranged within the spout between the sides thereof and extending entirely across the spout so as to be a closure therefor when the spout is 25 retracted.

2. A package one wall of which is formed with an opening, a pouring spout fitted in 30 said opening and adapted to be moved outward therein to pouring position and to be moved inward therein to a retracted position, and a closing flap separate from the 35 spout and connected with the wall of the package, and adapted to close the pouring space within the spout and the opening in the wall of the package when the spout is retracted and adapted to be moved to open 40 position when the spout is projected.

3. A package one wall of which is formed with an opening, a pouring spout fitted in 45 said opening and adapted to be moved outward therein to pouring position and to be moved inward therein to a retracted position, and a closing flap separate from the spout and connected with the wall of the 50 package, and adapted to close the pouring space within the spout and the opening in the wall of the package when the spout is retracted and adapted to be moved to open position when the spout is projected, the said spout having means for moving the said flap.

4. A dispensing package of the character described comprising a paper walled vessel having a sheet metal pouring spout slidably mounted in one wall thereof, said wall 55 being slotted to correspond to the size and shape of said spout, part of said wall bounded by the slit forming a pivoted flap to close the pouring opening, substantially as specified.

5. A dispensing package of the character described including a paper walled can having a sheet metal trough-shaped pouring spout slidably mounted in one wall thereof, said wall being slotted to correspond to the 60 size and shape of said spout and thereby forming a pivoted flap to close the pouring opening in said wall, and means for automatically swinging said flap outwardly when said spout is moved outwardly, substantially as specified.

6. A paper can having a sheet metal trough - shaped pouring spout slidably mounted in one end thereof, said end being slotted to correspond to the contour of the 75 spout and said spout being slidable in the slit, a portion of said end located within the pouring spout forming a pivoted flap to close the pouring opening, said spout having means thereon adapted to engage and swing 80 the flap to open position when said spout is pulled outwardly, substantially as specified.

7. A paper can having a sheet metal trough - shaped pouring spout slidably mounted in one end thereof, said end being 85 slotted to correspond to the contour of the spout and said spout being slidable in the slit, a portion of said end located within the pouring spout forming a pivoted flap to close the pouring opening, said spout having 90 means thereon adapted to engage and swing the flap to open position when said spout is pulled outwardly, and means on said spout for limiting its inward and outward movements, substantially as specified. 95

Signed this 21st day of November in the presence of two subscribing witnesses.
